COMPOSITE EXCAVATING AND EARTH DISTRIBUTING AND LEVELLING MACHINE

Andrew S. Kinsinger, Gordenville, Pa.

Application October 5, 1950, Serial No. 188,550

1 Claim. (Cl. 37—98)

My invention relates broadly to excavating machinery and more particularly to a trench digging and filling attachment for tractors.

One of the objects of my invention is to provide an attachment for tractors of the general class set forth in my co-pending application Serial Number 149,379 filed March 13, 1950 for Composite Excavating and Pipe Laying Machine with provision for controlling the width of the excavated trench and also for filling the trench after excavation and installation of cable, tile, pipe or conduit.

Another object of my invention is to provide an attachment for an excavating tool for tractors including a pair of wings which may be adjusted to cut a deep narrow ditch immediately behind the trench cut by the excavating tool.

Still another object of my invention is to provide an attachment for excavating tools comprising a pair of adjustable wings which may be utilized as a pusher by operating the tractor in reverse direction after an excavation operation for filling an open trench.

Still another object of my invention is to provide a composite excavating and filling attachment for trench diggers adapted for the rapid installation of tile, cable, conduit and pipe in the earth.

Other and further objects of my invention reside in the construction of adjustable wing attachment for trench diggers as set forth more fully in the specification herein-after following by reference to the accompanying drawings in which:

Figure 1 is a side elevational view of the wing attachment device for excavating tools arranged in accordance with my invention; Fig. 2 is a view showing the juxtaposed positions of the parts of the wing attachment device of my invention; Fig. 3 is a fragmentary vertical sectional view taken substantially on line 3—3 of Fig. 1; Fig. 4 is a fragmentary vertical sectional view taken substantially on line 4—4 of Fig. 1; Fig. 5 is a horizontal sectional view taken substantially on line 5—5 of Fig. 1; Fig. 6 is a fragmentary vertical sectional view taken substantially on line 6—6 of Fig. 5; Fig. 7 is a transverse sectional view taken substantially on line 7—7 of Fig. 1; Fig. 8 is a transverse sectional view taken substantially on line 8—8 of Fig. 1; Fig. 9 is a transverse sectional view taken substantially on line 9—9 of Fig. 1; Fig. 10 is a detail view showing more clearly the manner of attaching the brace bar which extends between the depending support for the digging tool and the frame of the attachment; Fig. 11 is a fragmentary vertical sectional view taken substantially on line 11—11 of Fig. 10; Fig. 12 is a rear perspective view of the attachment of my invention showing the wings moved to minimum spacial relation and illustrating in dotted lines the maximum position to which the wings may be displaced; Fig. 13 is a view similar to the view shown in Fig. 12 but illustrating the wings moved to an intermediate spacial position; Fig. 14 is a vertical sectional view through the wings and the mounting means therefor in accordance with the arrangement shown in Fig. 13; Fig. 15 illustrates the attachment of my invention used

2

in coaction with the excavating tool as a plow as the excavating tool is advanced through the earth under pressure force developed by the pull of the tractor; and Fig. 16 is a view illustrating the attachment of my invention used as a pusher with the tractor operating in a reverse direction to the direction of operation represented in Fig. 15 for filling a trench after an excavating operation.

My invention is directed to an attachment for excavating machines which may be utilized in a dual capacity; 10 that is, as a plow in effecting the enlargement of a trench dug by an excavating tool for the laying of tile, pipe, conduit, or cable and which may also be utilized as a pushing tool for filling earth into an open trench after the excavating operation. I provide a pair of pivotally mounted 15 wings which are attachable to the rear of the excavating tool and which may be angularly adjusted to selected spacial positions for enlarging a trench cut by the excavating tool as the excavating tool is advanced through the earth. The same spacially related wings are utilized in 20 accordance with my invention for filling and covering the excavated trench with dirt by reversing the direction of movement of the tractor and using the wings as a pusher.

Referring to the drawings in more detail, reference character 1 designates a frame structure terminating in quadrilaterally spaced lugs 2, 3, 4 and 5 for connection with the hydraulic lift of a tractor. The frame structure 1 carries the centrally disposed I beam 6 having laterally extending flange portions 6a and 6b. The flange portion 6b of I beam 6 is slotted adjacent opposite sides of the web of the I beam for the passage of downwardly extending plate members 7 and 8 which are secured by transversely extending bolt 9 at their upper ends to the I beam 6 and which carry at their lower extremities the cutting blade 10 and the front cutting bar 11. The cutting blade 35 10 is supported by a block 12 which extends rearwardly of plates 7 and 8 and is provided with a vertically extending socket 14 therein adapted to detachably receive the pintle 15 of the pivoted wing assembly of the attachment of my invention. The pivoted wing assembly 40 is carried by a mounting block 16 which is shaped to fit behind the plates 7 and 8 and to enter the recesses 7a and 8a in plates 7 and 8 as shown more clearly in Figs. 1, 2 and 7. The mounting block 16 is provided with a pair of straps shown at 17 and 18 at opposite sides thereof and projecting forwardly therefrom and embracing the downwardly extending plates 7 and 8 and the yoke-shaped 45 end 19 of brace bar 20. The yoke-shaped end 19 of brace bar 20 fits immediately around depending plates 7 and 8 and beneath the plates 17 and 18. A confining bolt member 21 extends through plate 17 and 18 and yoke 19 and through the plates 7 and 8 for maintaining the several component parts in assembled relation. Brace bar 20 is provided with a yoke 22 at the upper end thereof embracing the strap 23 through which the confining bolt 24 50 carried by yoke 22 extends. Bolt 24 is inserted after members 20 and 23 are brought into position to receive it. Strap 23 is welded at 23a to the bottom flange 6b of I beam 6. Thus a substantial assembly is provided between the excavating tool, the frame 1 and the wing attachment 55 for resisting the stresses encountered during excavating operations.

The attachment of my invention includes the two shaped wings 26 and 27 having vertically extending portions 26a and 27a and horizontally extending portions 26b and 27b. The forward peripheral edges of the wings 26 and 27 terminate in sections of a hinge represented at 26c and 27c which coact with alternately disposed hinge sections 16' and 16" carried by opposite peripheral edges of the mounting block 16. These coacting hinge sections are interconnected by hinge pintles 28 and 29 60 around which the wings 26 and 27 may be oriented to selected adjusted positions.

The mounting block 16 carries a rearward tapered extension 16''' thereon projecting between the wings 26 and 27 in a plane that is substantially coplanar with the planes of the lowermost bars of the sets of parallel bars 33 and 34 and forming a connection plate for the links 31 and 32. The links 31 and 32 are pivoted at 31a and 32a with respect to plate 16''. The pivotal connections 31a and 32a are constituted by bolt members which extend downwardly terminating in flat plate members 31a' and 32a' as shown more particularly in Fig. 6. The flat plate members 31a' and 32a' extend below the lowermost bars of the sets of spaced parallel bars 33 and 34 and form tool engagement means enabling the bolt members to be readily gripped when detaching or attaching the bolt members. The outer extremities of links 31 and 32 extend between the spaced parallel bars 33 and 34 carried by the inside plane-like walls of the wings 26 and 27. These sets of spaced parallel bars are provided with apertures in spaced positions along the lengths thereof as represented at 33a, 33b, 33c, 33d and 33e and at 34a, 34b, 34c, 34d and 34e.

The sets of spaced parallel bars 33 and 34 are welded to the vertically extending portions of the wings 26 and 27 and have their lowermost sections provided with angularly extending tapered projections 33f and 34f that are welded to the lowermost portions of the wings 26 and 27 for substantially reinforcing the wings. The links may be moved to any of the positions provided by the apertures 33a-33e and 34a-34e and fixed in the selected positions by removable pins 35 and 36 which are secured in set positions by cotter pins. Fig. 12 shows the wings set for performing the function of a plow in the minimum spaced positions behind the excavating tool 10 with the links 31 and 32 in position. The wings may be further collapsed by removing or disconnecting links 31 and 32 whereupon the lowermost bars of the sets of parallel bars 33 and 34 move into edge to edge abutting relation with the opposite tapered edges of the coplanar tapered plate 16''. The dotted line position shows the maximum spread for the wings.

Figs. 13 and 14 show the wings moved to an intermediate position with the links 31 and 32 fastened at 33c and 34c for determining the width of the trench that is to be excavated behind the excavating tool, or the amount of fill desired to be moved when the wings are used as pushers.

Figs. 15 and 16 show the two alternate positions of the device of my invention. In Fig. 15 the wings are shown partially spread and operating as a plow behind the excavating tool 10 as a pressure force puller drawn by a tractor. In Fig. 16 the reverse operation is shown where the tractor moves in reverse to push the wings which are spread to the desired width for pushing the dirt as the tractor moves and distributing the dirt back into an open trench. The effective spread of the wings is selected in accordance with the width of the trench to be filled and leveled.

While I have described my invention in certain of its preferred embodiments which have been found to be particularly useful in operation, I realize that modifications may be made in details of construction and I desire that it be understood that no limitations upon my invention are intended other than may be imposed by the scope of the appended claim.

What I claim as new and desire to secure by Letters Patent of the United States is as follows:

An attachment for excavating machines comprising a mounting block having major and minor axes with the major axis disposed in a substantially vertical plane, and rear spaced corner portions at opposite ends of the minor axis, hinge means mounted on both of the rear spaced corner portions of said block, a pair of plates having hinge means on their leading edges complementary to and connected with the hinge means on said block, a tapered plate member extending transversely of said block from a width corresponding substantially to the distance between the spaced corner portions of said block to a width determining the minimum spread of said plates when in collapsed position, said plate member projecting rearwardly from said block along a central axis coplanar with the minor axis of said block and intermediate each of said hinge means, linearly extending means carried by said plates in coplanar alignment with said tapered plate member, adjustable connection means extending between said plate member and said linearly extending means for adjusting and maintaining the angular relation of said plates and a bracing member integral with said linearly extending means and coextensive with the associated plate for reinforcing said plate with respect to the adjustable connection means extending to said plate member, said linearly extending means consisting of a pair of substantially parallel spaced bars connected with the rear surface of the associated plate and wherein said bracing member extends from the end of one of said bars in an angular direction away from said bar and is connected with the rear surface of the associated plate for reinforcing said plate.
